United States Patent Office

Des. 197,836
Patented Mar. 31, 1964

197,836

FORCE CUP

Stanley B. Gross, Philadelphia, Pa., assignor to Hancock Gross, Inc., Philadelphia, Pa., a corporation of Pennsylvania

Filed Aug. 26, 1960, Ser. No. 61,899

Term of patent 14 years

(Cl. D9—2)

Fig. 1.

Fig. 2.

FIG. 1 is a top plan view of a force cup showing my new design.

FIG. 2 is a side elevation of same.

The dominant features of my design reside in the portions shown in full lines.

I claim:

The ornamental design for a force cup, as shown and described.
